DOOR FASTENER

Louis C. Clair, Palestine, Tex., assignor, by direct and mesne assignments, of three-sixteenths to J. S. Loftin, Dallas, three-sixteenths to R. F. Peterson, Palestine, and three-sixteenths to C. Rompy, Houston, Tex.; one thirty-second to J. Melton Oakes and one thirty-second to E. A. Campbell, both of Homer, La.

Application January 23, 1948, Serial No. 3,985

7 Claims. (Cl. 292—181)

1.

My invention relates to locks generally but more particularly to fasteners adapted in structure and operation for application to refrigerator doors and the like, whereby such doors may be locked and unlocked from the outside, and whereby an operator, who might be accidentally locked inside, may easily unlock the door and free himself from what might constitute a dangerous imprisonment.

It is an object of my invention to provide a fastener that is of rugged construction and able to withstand severe use on the heaviest of doors.

It is a further object of my invention to provide a fastener that is simple to manufacture, easy to install and which is not ungainly in appearance when attached to the doors of refrigerator rooms or trucks, or some other door such as a vault where an operator is likely to be locked inside either during or after working hours.

It is another object of my invention to provide a door fastener which may be locked from the outside with a padlock or the like and yet permit an operator accidentally imprisoned behind such door to release himself and relock the door from the outside without removing the padlock.

Further objects and advantages will be found in the following detailed description when viewed together with the accompanying drawings in which:

Fig. 1 represents a front elevation of a door fastener embodying my invention shown as applied to a door.

Fig. 2 is a top plan view of the fastener shown in Fig. 1.

Fig. 3 is a cross-sectional view through a portion of a door and door jamb showing the installation of the fastener.

Fig. 4 is a similar view of Fig. 3, the fastener being disengaged from the inside to permit the door to open as shown, and

Fig. 5 is a vertical sectional view taken substantially on line 5—5 of Fig. 2.

As shown in Fig. 1 numeral 10 designates a door and numeral 11 the door jamb. Numeral 12 designates a keeper held to the door by screws 13. The keeper 12 is provided with a beveled leading edge 14.

Fastened to the outside face of the door jamb 11 is the fastener housing designated generally by the letter H. The housing H consists in a flat plate 15 held against the door jamb 11 by mounting screws 16. Either removably or integrally attached to the flat plate 15 is a plunger barrel 17 bored to slidably receive a piston 18. The rear end of the plunger barrel 17 is closed.

by a plug 19. A portion of the plunger 20, in this instance, is made square in cross section and extends through a square hole provided in both the plug 19 and the piston 18. The plunger 20 is further provided with a head 21 on the rear end and a beveled face 22 matching the keeper face 14 on its opposite end. I have arranged a compression spring 23 to encircle the rear portion of the plunger 20 having one of its ends abutting against the plug 19 and the other against the head 21 of the plunger 20.

On the inside of the plunger barrel 17 and encircling the plunger 20 between the face of the plug 19 and the rear end of the piston 18 is a retaining ring 24. Thus, when an operator presses against the head 21 of the plunger to compress the spring 23, the retaining ring 24 presses against the piston 18 which is normally housed within the forward or open end of the barrel 17 to slide it forward in the plunger barrel 17.

The first mounting plate 15 is provided with a recess 25 in which an L-shaped latch 26 is pivotally mounted. One leg of the latch 26 is arranged to enter a slot 27 in the plunger barrel 17 and rest in a notch 28 provided on the circumferential surface of the piston 18. The opposite leg of the latch 26 rests on a small compression spring 29 mounted also in the recess 25 of the flat plate 15.

Extending horizontally through the door jamb 11 is the inside release pin 30 slidably mounted in the flat plate 15 on one end and in a bearing cap 31 on the other end. The pin 30 is further provided with a retaining ring 32 which prevents the pin from being removed from its position in the door jamb and becoming lost or misplaced.

The forward end of the plunger 20 is provided with a hole 33 through which a retaining pin 34 may be placed to keep the door closed. This retaining pin 34 is preferably provided with a chain 35 or the like attached to its upper end and securely fastened to the door jamb 11. There may even be a rack 36 fastened to the jamb 11 into which the retaining pin 34 may be placed when the mechanism is not in use. It must be remembered that the device is designed for use preferably in combination with a conventional latch which is employed to keep the door closed during periods of normal usage.

From the above description it can be seen that with the pin 34 placed in the hole 33 of the plunger 20, the door cannot be unlocked except from the inside or by removing the pin. In order to lock the door from the outside, I simply use

an ordinary padlock 31 through the pin 34. Let us suppose, however, that a workman has been accidentally locked behind a door after the padlock has been applied. The accidentally imprisoned workman would simply press on the release pin 30 to effect the release of the latch 26. The releasing of the latch 26 from engagement with the groove 28 in the piston 18 would allow the compressed spring 23 to draw both the piston 18 and the pin 33 and its attached padlock 37 backward to allow the beveled edge 22 of the plunger 20 to clear the keeper 12 on the door as illustrated in Fig. 4. Note that the plunger barrel 17 is provided with elongated slots 38 to slidably receive the pin 34. After the imprisoned workman has released himself, he presses on the head 21 of the plunger 20 from the outside of the door and the mechanism again locks itself without ever having to remove the padlock 37. Now it can be seen that anyone desiring to again enter the locked door must unlock the padlock 37; but at the same time, any one locked behind such door is able to release himself according to the procedure just described.

While I have described my invention in detail as applied to vault doors or the like, it is to be understood that other applications may be made and various changes in the construction and arrangement of parts resorted to without departing from the spirit and scope in my invention as defined by the following claims.

I claim:

1. A door lock comprising a substantially flat plate adapted for mounting on the outside facing of a door jamb, a horizontally disposed barrel attached to said plate, a piston slidably mounted in said barrel, a plunger slidably mounted in said piston, said plunger provided with an enlarged head on one of its ends, a compression spring encircling said plunger and interposed between said enlarged head and said barrel, said spring adapted to move said plunger from a forward to a retracted position, the forward end of said plunger extended beyond the outer end of said piston and adapted to be moved beyond the edge of a door to hold the same in a closed position, means for locking said piston in said barrel and means for locking said plunger in said piston.

2. A door lock comprising a substantially flat plate adapted for mounting on the outside facing of a door jamb, said plate provided with an open recess on the outer face thereof, a horizontally disposed barrel attached to said plate across said open recess, said barrel provided with a slot communicating with the open recess of said plate, a piston slidably mounted in said barrel, a plunger slidably mounted in said piston, said plunger extended through said piston and said housing and provided with an enlarged head on one of its ends, a compression spring encircling said plunger and interposed between said enlarged head and said barrel, said spring adapted to move said plunger from a forward to a retracted position, said plunger being made long enough for its forward end to extend beyond the edge of a door to hold the same in a closed position when said plunger is moved to a full stroke in opposition to said compression spring, said piston provided with a notch, a stop on said plunger adapted to engage the rear end of said piston to move the same forwardly as said plunger is being moved beyond the edge of said door, a pawl pivotally mounted in the recess of said plate, a spring adapted for urging said pawl into a locking engagement with the notch of said piston, means for locking said plunger to said piston, and means for unlocking said door from a position inwardly thereof comprising a release bar slidably mounted through the opposite face of said door jamb and said flat plate, the inner end of said release bar being aligned for engagement with said pawl, whereby an inward movement of said release bar will overcome the spring of said pawl to release the pawl from its locked position in the notch of said piston.

3. A door lock comprising a substantially flat plate adapted for mounting on the outside facing of a door jamb, said plate provided with an open recess on the outer face thereof, a horizontally disposed barrel attached to said plate across said open recess, said barrel provided with a slot communicating with the open recess of said plate, a piston slidably mounted in said barrel, a plunger slidably mounted in said piston, said plunger provided with an enlarged head on one of its ends, a compression spring encircling said plunger and interposed between said enlarged head and said barrel, said spring adapted to move said plunger from a forward to a retracted position, the forward end of said plunger extending beyond the outer end of said piston a sufficient length to extend beyond the edge of a door to hold the same in a closed position when said plunger is moved into its forward position, said piston provided with a notch, a pawl pivotally mounted in the recess of said plate and adapted to engage the notch of said piston through said slot, means for locking said plunger to said piston, and means extending through the opposite facing of said jamb for releasing said pawl from its engagement with the notch of said piston, whereby said piston and said plunger may be moved by said compression spring to unlock said door.

4. A door lock comprising a flat plate adapted for mounting on the outside facing of a door jamb, said plate provided with an open recess on the outer face thereof, a horizontally disposed barrel attached to said plate across said open recess, said barrel provided with a slot communicating with the open recess of said plate, a piston slidably mounted in said barrel, a plunger slidably mounted in said piston, said plunger extending through said piston and said housing and provided with an enlarged head on its rear end, a compression spring encircling the rear end of said plunger and interposed between said enlarged head and said barrel, said spring adapted to move said plunger from a forward to a retracted position, the forward end of said plunger extending beyond the forward end of said piston a sufficient length to be moved beyond the edge of a door to hold the same in a closed position when said plunger is moved in opposition to said spring into its forward position, said piston provided with a notch, a stop on said plunger adapted to engage the rear end of said piston to move the same forwardly as said plunger is being moved forwardly, a pawl pivotally mounted in the recess of said plate, a spring adapted for urging said pawl into a locking engagement with the notch of said piston, means for locking said plunger to said piston, and means for unlocking said door from a position inwardly thereof comprising a release bar slidably mounted through the opposite face of said door jamb and said flat plate, the inner end of said release bar being aligned for engagement with said pawl, whereby an inward movement of said release bar will overcome the spring of said pawl to release the pawl from its locked position in the notch of said piston.

5. The combination with a door having a keeper thereon and a door jamb, of a door lock comprising a plate mounted on the outside facing of said jamb opposite said keeper, a horizontally disposed barrel attached to said plate, a piston slidably mounted in said barrel, a plunger

slidably mounted in said piston, said plunger extending through said piston and said barrel and provided with an enlarged head on the rear end thereof, a compression spring encircling the rear end of said plunger and interposed between said enlarged head and said barrel, said compression spring adapted to hold said plunger in a normally retracted position in said piston, stop means on said plunger adapted for engagement with said piston when said plunger is moved forwardly in the same to move said piston forwardly in said barrel, means for locking said piston in its forward position, the forward end of said plunger provided with a hole positioned slightly forward of the outer end of said piston, a locking pin removably mounted in the hole of said plunger, the forward end of said plunger being made long enough to extend across said keeper to hold said door in a closed position and means for unlocking said piston from a position on an opposite side of said door permitting its withdrawal by said compression spring whereby said door may be opened without removing said locking pin.

6. The device as claimed in claim 5 wherein a portion of said plunger is made square in cross section and wherein said barrel is provided with a square opening in one end adapted to slidably receive said plunger.

7. In a door lock of the class described, the combination of a plate adapted to be fastened to the outside facing of a door jamb, a barrel horizontally mounted on said plate, a piston slidably mounted in said barrel, a plunger slidably mounted in said piston, said plunger extending beyond the outer extremities of said piston and said barrel and provided with an enlarged head on one end and a beveled face on the opposite end and in which end is a hole adjacent to the forward end of said piston, said plunger adapted to be

moved forwardly in said piston and said housing to a point where said beveled face will register with a keeper mounted on said door, said piston provided with a notch adapted to register with a piston locking means for holding said piston in a forward, locked position, a helical compression spring mounted on said plunger and interposed between said enlarged head and said barrel, a stop on said plunger adapted to engage said piston to move the same into its forward locking position as said plunger is moved across said door, means for locking said plunger to said piston consisting in a pin slidably inserted in said hole in the forward end of said plunger, and means for disengaging said piston locking means to open said door from the inside, comprising a release bar slidably mounted through the opposite facing of said door jamb and said plate, the inner end of said release bar being adapted for engagement with said piston locking means in a manner whereby an inward movement of said release bar will disengage said piston locking means from said notch, said barrel provided with an elongated slot adapted to slidably receive said pin upon the withdrawal of said piston and said plunger locked in the same by said pin at one end and said stop at its opposite end.
